FEEDING APPARATUS

Charles S. Walker, Clearwater, Fla., assignor to
Bronson C. Skinner, Dunedin, Fla.

Application February 12, 1942, Serial No. 430,530

9 Claims. (Cl. 198—26)

The present invention relates to feeding apparatus and, more particularly, to such apparatus for feeding globular objects to relatively moving receivers at a receiving point.

A general object of the present invention is the provision of simple and economically constructed feeding apparatus adapted efficiently to feed substantially globular objects, such as citrus fruit or the like, to moving receivers whereby they are accurately and securely located in receiving recesses effectively to be carried to operating stations without damage and with the elimination of any necessity of a particular spacing of receiving recesses, speed of movement or timing thereof.

A more specific object of the invention is the provision of such feeding apparatus characterized by means adapted under certain conditions for rotating in a certain direction, relative to direction of movement of successive receiving recesses of a receiver, globular objects fed by gravity down an elevated way or chute whereby their movement is retarded and they are caused accurately and securely to be located in the receiving recesses without undue bouncing.

Other objects of the invention will in part be obvious and will in part appear hereinafter.

The invention accordingly comprises the features of construction, combination of elements, and arrangement of parts, which will be exemplified in the construction hereinafter set forth, and the scope of which invention will be indicated in the claims.

For a fuller understanding of the nature and objects of the invention reference should be had to the following detailed description taken in connection with the accompanying drawing, in which:

Fig. 1 is a side elevational view with parts in section and parts broken away of one modification of the present invention exemplifying one type of receiver that may be used;

Fig. 2 is an end elevational view with parts broken away and in section of the structure shown in Fig. 1; and

Fig. 3 is an end elevational view of a modified form of the invention characterized by a bank of feeding devices associated with a bank of receiving recesses.

Some of the difficulties attendant upon placement of globular objects, such as oranges or the like, in moving cup-like receivers, especially those arising when citrus fruits are placed in such receivers to be carried to treating apparatus, have been pointed out in the United States patent of

Skinner et al., No. 2,283,615, issued May 19, 1942. One problem is a tendency of such objects to bounce out of the moving receivers. Where the feeding means comprises a chute, the objects may have a tendency to bounce and become jammed between the side of the chute, or other fixed structure, and the rim of a receiving recess of the moving receiver. Careful timing is also frequently required.

10 The present invention efficiently overcomes these and other problems and difficulties in a simple and efficient manner. It comprises a rotated retard roller located in a certain manner at the bottom of an elevated chute or way adapted to feed objects to a receiver having successive cup-like recesses adapted to be moved continuously or intermittently.

The retard roller which may be inserted in an opening in the side of the elevated chute at the bottom thereof checks or breaks the fall of the objects from the chute into the receiver, thus minimizing bouncing. Furthermore, the roller is rapidly rotated, thus giving any object that may contact it a reverse spin, and cause it to move away toward the opposite side of the chute. Thus, any object falling down the chute will, when it contacts the roller, be spun away from it, and will repeatedly be caused to assume a position adjacent the opposite side of the chute until it falls past the roller. Likewise, any object which has dropped past the axis of the roller, and which rests on the moving receiver with a tendency to be carried thereby toward the roller, will upon contact with the roller be spun back from it, and be rolled back along the top of the receiver into an empty cup or receiving recess when the latter is presented, thus avoiding any tendency of the object to roll forward with the receiver without being properly located in a receiving recess or to be caught or jammed between the edge of the chute or adjacent stationary structure and the lip of a cup or receiving recess.

In the drawing like numerals refer to like parts throughout. As shown in Fig. 1, a receiver 10 may be a cylinder 11 fixedly mounted on a horizontal axle 12, supported by suitable framework 13, and rotated by power applied through a pulley 14. The cylinder 11 has in its surface 15—15 a number (six are shown by way of example) of cups or receiving recesses 16—16, which preferably are symmetrically located on the circumference of the cylinder as shown, although such symmetrical placement is not necessary. Each cup 16 is the proper size to receive any one of a

group of sized globular objects such as citrus fruits, or more particularly, an orange A.

This receiver 10 may cooperate with suitable mechanism for halving the fruit and extracting the juice, or otherwise operating thereon at succeeding stations, and the objects, e. g. oranges, may be supplied from any suitable source which may include a sizer belt over which the fruit is run to and under a sizer roll, then down a sloping way wherein it is arranged in single file, all as understood in the art.

The fruit, aligned as just described, may then be picked up by any suitable conveyance, such as an endless belt 17, carried to a chute 18, and deposited therein in some suitable fashion, such as by spilling off the belt as it travels over a roller 19, which may be utilized to drive the endless belt.

The chute 18 has an entrance 20, a delivering end 21 terminating just above the cylindrical receiver 10 at a receiving point, and an intermediate section 22 down which the objects travel by gravity from the entrance 20 to the delivering end 21. Obviously the section 22 need not be located vertically as shown. It is merely necessary that the chute be so shaped as to provide a gravity feeding way.

At the delivering end 21 of the chute, a portion of the trailing side of the chute is removed and a retard roller 23 is inserted, with its axis located substantially parallel to an element of the surface of the receiver 10. This roller 23 is spaced from the trailing side of the chute a distance such as to permit any of the fed objects to move by gravity past it to the receiver. The distance between any portion of the surface of a cup or recess 16 and an opposed portion of the surface of the roller 23 is slightly more than the distance between that portion of the cup surface and the opposed portion of the protruding surface of any object to be located therein; so that the objects will pass freely beneath the roller when they are properly seated in the receiving cups and the latter carried away therefrom by movement of the receiver.

The retard roller 23 may be fixedly mounted on a shaft 24, rotated by power applied through a belted pulley 25 and journaled to the chute 18 as shown. The roller 23 is rotated fast enough to give it a peripheral velocity of not less and preferably greater than the linear velocity of the cups 16-18. In practice, the roller 19, the receiver 10, and the retard roller 23 are all preferably driven by the same power source, the relative speeds being determined by pulleys of proper size in the manner well known in the art. This practice is merely the simplest and the most economical, and is not essential to the invention.

The retard roller 23 is preferably a hyperboloid as illustrated in Fig. 2. When the roller is so shaped, it has the further advantage of tending to center the objects regardless of the shape of the chute 18, so that they fall into the middle of the cups to be properly located and securely seated therein. The retard roller 23 is preferably made of hard or unyielding material, but it may be formed of or surfaced with a somewhat resilient material, such as rubber or the like.

Furthermore, the roller 23 has been shown as having its shaft fixedly located by way of example. It might also be floatingly located, such as by location of the ends of shaft 24 in horizontal, vertical or upwardly and outwardly sloping slots, 75

with bias applied by either a spring or gravity as desired. Such a mounting would more readily permit over-sized oranges to pass and be fed to the receiver.

Such feeding apparatus may be used to advantage in feeding a plural banked receiver, such as 110, having several staggered rows of receiving cups 116, 216, 316, as shown in Fig. 3. When the feeding apparatus is used with this kind of a receiver, similar to that proposed in the above-identified application for reasons therein indicated, there is no need for carefully timed feeding mechanism usually employed to deposit an object in each pocket in properly timed relation.

To bring the objects to chutes 118, 218 and 318 there is preferably a single endless belt 117 running over a broad roller 119. The oranges are deposited into chutes 118, 218 and 318, which may be formed by the provision of dividing partitions 26, 28 in a wide chute 180.

Retard rollers 23-23 are located and operated at the bottoms of chutes 118, 218 and 318 similar to the location and operation of roller 23 with respect to chute 18. Obviously the working retard roller surfaces for the plurality of chutes may be provided on a single roller.

Since each retard roller will permit objects to drop into empty cups only as the latter come beneath the end of each chute, no other timing mechanism is needed, regardless of how the receiving recesses are arranged in any row, and regardless of how the rows are arranged with respect to each other.

It will be understood that the receiver need not be of the drum type as shown by example. A continuous or endless moving belt having receiving cups or recesses depressed into or provided in its surface with a reach thereof, located beneath the feeding device of the present invention so as to move the cups or recesses therepast in a direction from the leading side of the chute to the trailing side thereof where the retard roller is located, may be employed within the scope of the present invention.

It will accordingly be seen that the objects set forth above and those indicated thereafter are efficiently attained by the apparatus of the present invention and since certain changes may be made in the above construction and different embodiments of the invention could be made without departing from the scope thereof, it is intended that all matter contained in the above description or shown in the accompanying drawings shall be interpreted as illustrative and not in a limiting sense.

It is also to be understood that the following claims are intended to cover all of the generic and specific features of the invention herein described, and all statements of the scope of the invention which, as a matter of language, might be said to fall therebetween.

Having described my invention, what I claim as new and desire to secure by Letters Patent is:

1. A feeding device comprising, in combination, a receiver having receiving recesses adapted to receive globular objects dropped thereinto, a way down which the objects travel in single file to a receiving point, means for providing relative motion between said way and said receiver, means to maintain a supply of objects in said way, and a rotated retard roller at the bottom of the way adapted reversely to spin each object as it contacts said roller.
2. A feeding device comprising, in combination,

a receiver having recesses adapted to receive rotatable objects, a chute down which the objects travel in single file to a receiving point, means for providing relative motion between said chute and said receiver, means to maintain a supply of objects to the chute, a retard roller located on the trailing side of the chute at its bottom, and means to rotate said roller in a direction so that its surface adjacent the path of the objects down said chute travels upwardly.

3. A feeding device comprising, in combination, a receiver having receiving recesses adapted to receive globular objects, a chute down which the objects travel in single file to a receiving point, means for providing relative motion between said chute and said receiver, means to maintain a supply of objects to the chute, a retard roller located on the trailing side of the chute at the bottom, and means to rotate said roller in a direction so that its surface adjacent the path of the objects down said chute travels upwardly and at a peripheral linear speed not less than the linear speed of the receiver at the receiving point.

4. A feeding device comprising, in combination, a movable receiver having cup-shaped recesses in its surface adapted to receive globular objects, a chute down which the objects are adapted to fall in single file, means to maintain a supply of objects in said chute, a retard roller located in the trailing side of the chute at the bottom, and means to rotate said roller in a direction so that its surface adjacent the path of the objects down said chute travels upwardly and at a peripheral velocity not less than the peripheral velocity of the receiver.

5. A feeding device comprising, in combination, a movable receiver having cup-shaped recesses in its surface adapted to receive globular objects, a chute down which the objects are adapted to fall in single file, means to maintain a supply of objects in said chute, and a rotated retard roller located in the trailing side of the chute at the bottom spaced a distance from the leading side of said chute sufficiently to permit downward passage of the objects and located sufficiently above said receiver to permit the objects freely to pass underneath said roller when the objects are properly seated in the receiving cups.

6. A feeding device comprising, in combination, a movable receiver having cup-shaped recesses in its surface, a vertical chute terminating just above the surface of said receiver, means to maintain a supply of globular objects in single file in the chute, and a roller inserted in the trailing side of said chute spaced a distance from

the leading side of said chute sufficiently to permit downward passage of the objects and located sufficiently above said receiver to permit the objects to pass freely underneath said roller when the objects are properly seated in the receiving cups, and means to rotate said roller in a direction so that its surface adjacent the path of the objects down said chute travels upwardly and at a peripheral velocity not less than the peripheral velocity of the receiver.
